UNITED STATES PATENT OFFICE

MARIE D. AABERG, OF LAWTON, NORTH DAKOTA.

ENVELOP.

1,057,910.

Specification of Letters Patent. Patented Apr. 1, 1913.

Application filed February 8, 1912. Serial No. 676,358.

To all whom it may concern:

Be it known that I, MARIE D. AABERG, a citizen of the United States, residing at Lawton, in the county of Ramsey, State of North Dakota, have invented certain new and useful Improvements in Envelops; and I do hereby declare the following to be a full, clear, and exact description of the invention, such as will enable others skilled in the art to which it appertains to make and use the same.

This invention relates to new and useful improvements in envelops.

The primary object of the invention is to form the envelop of a blank of novel formation and which can be stamped from sheet material; the invention being especially designed for producing a box like envelop whereby increased packing space is provided for the sending of parcels or articles of merchandise through the mails.

Another object of the invention is to construct an envelop having considerably more packing space than an ordinary envelop and also to provide novel means for holding the envelop closed.

With the above and other objects in view, the invention consists in the combinations and arrangements of parts to be hereinafter more clearly described, claimed and illustrated in the accompanying drawings, in which,

Figure 1 is a perspective view of my improved envelop sealed ready for use. Fig. 2 is a perspective view of the envelop with the closing flap in a raised position and showing the envelop slightly collapsed before being sealed. Fig. 3 is a vertical sectional view of the envelop. Fig. 4 is a plan view of a blank from which the envelop is formed. Fig. 5 is a longitudinal sectional view of the envelop. Fig. 6 is an enlarged detail view of fastening eye or plate carried by the closing flap. Fig. 7 is a similar view of a tongue carried by the front portion of the envelop for engaging said eye or plate and holding the envelop closed.

Referring to the drawings in detail there is shown my improved envelop which is formed of a blank section of material suitably stamped from a sheet of paper or the like and comprising a front portion 10 and a back portion 11, the said front portion and back portion having the bottom 12 of the envelop formed contiguous with their lower edges. The bottom portion 12 is

formed at its end with tongues 13 and the bottom and these tongues are formed with a central longitudinal crease or weakening line 14 forming a folding line for the bottom 60 adapted to be extended inwardly between the front and back portions so that they will be capable of collapsing so as to occupy a minimum amount of space when packed. The back portion 11 is formed with integral side 65 flaps 15 which are adapted to bend forwardly along the folding lines 16 and each of these side flaps 15 is formed with a supplemental flap 17 bent along the folding lines 18 parallel to the lines 16 and said 70 flaps 17 are covered with a suitable adhesive substance by which they are secured to the inner face of the front portion of the envelop vertically of its side portions and thereby form a box like structure or receptacle. The tongues 13 are then bent along the folding lines 19 which are disposed contiguous with the folding lines 16 and are covered with a suitable adhesive substance on their inner faces by which they are secured to the outer faces of the side flaps 15 75 near their lower ends. By this construction the central longitudinal crease or weakening line 14 will lie coincident with a central vertical crease or weakening line 20 in each of the side flaps 15, with respect to the portions of said line 14 which extend through the tongues 13 when the latter are folded upwardly and secured to the side flaps and when the envelop is folded along the lines 90 14 and 20 the upper ends of the side flaps 15 will fold downwardly along the inclined folding lines 21 extending from the upper corners of the side flaps 15 to the central folding lines 20 and at right angles to each 95 other so that the intermediate portions 22 of the folding lines 20 formed in the side flaps 15 will lie transversely of the envelop parallel to the upper edges of the front and back portions thereof.

The back portion 11 is formed with a top or cover flap 23 which is foldable downwardly along the line 24 to close the top of the envelop and this flap 23 is formed with a sealing or closing flap 25 which is bent along the line 26 and is coated with a suitable adhesive substance on its inner face whereby it may be attached to the outer face on the front portion 10 if desired. The top flap 23 is also formed with side flaps or tongues 27 which are foldable along the lines 28 coincident with the folding lines 16,

so as to be secured to the outer faces of the side flaps 15 by an adhesive substance covering the inner faces of the tongues 27 or these tongues may be extended along the 5 inside of the side flaps 15 as desired.

In order to more securely hold the closing flap 25 sealed, a securing eye or plate 29 is provided and said plate is of substantially rectangular form except that it has corner 10 prongs 30 forming an approximately star-shaped member and said prongs are extended through the closing flap and rebent if desired to secure the plate against the outer face of said flap. The plate 29 is further 15 provided with a central opening 31 disposed over a corresponding opening in the closing or sealing flap and engaged by the free extremity of a securing tongue 32 which has its opposite extremity formed with an end 20 prong 33 and side prongs 34 which are extended through the front portion of the envelop adjacent its bottom edge so that the free end of the tongue will extend upwardly and when engaged through the plate 25 29 may be rebent downwardly and thus hold the envelop in a closed position. It is also obvious that the plate 29 and the tongue 32 may be formed from single blank sections of metal so that the same can be 30 cheaply manufactured and also readily attached to the envelop. It will also be evident that when the envelop is folded and the top flap 23 is folded along the central longitudinal crease 35 that the end tongues 27 35 will fold inwardly and engage in the pockets formed by the inclined folding lines 21 in the side flaps so as to retain the envelops in shape when they are compactly folded for shipment and in which case they will occupy 40 a minimum amount of space.

What is claimed is:

1. An envelop formed of a blank comprising a front portion and a back portion, a bottom portion connecting said front and back portions and having integral side tongues, side flaps formed with the back portion and having supplemental flaps secured to the front portion, said side tongues being secured to said flaps to form a box like receptacle, a top flap carried by the back portion and having side tongues adapted to lie adjacent said side flaps and a closing flap carried by the top flap and secured to the front portion.
- 55 2. An envelop formed with front and back portions of similar shape and connected at the lower edges by a bottom portion having a central longitudinal folding crease, said bottom portion having end tongues 50 foldable thereon and having said crease extending thereinto, side flaps formed with the back portion and having attaching portions

at their free ends secured to the inner face of the front portion, said side flaps having central vertical folding creases lying coincident with the creases in the end tongues when the latter are secured to the outer faces of the end flaps to permit the envelop to collapse with the front and back portions in contact, said side flaps also having inclined folding creases between their upper corners and their central creases to fold downwardly and outwardly, a cover flap carried by one of said portions and having a central folding crease permitting it to extend into said downwardly folded portions of the side flaps and a sealing flap for the envelop.

3. An envelop formed of a blank comprising a front portion and a back portion, a bottom portion connecting said front and back portions and having integral side tongues, side flaps formed with the back portion and having supplemental flaps secured to the front portion, said side tongues being secured exteriorly to the lower portions of said flaps to form a box like receptacle, a top flap carried by the back portion and having side tongues secured exteriorly to the upper portions of said side flaps and a closing flap carried by the top flap and secured to the front portion.

4. An envelop formed with front and back portions of similar shape and connected at the lower edges by a bottom portion having a central longitudinal folding crease, said bottom portion having end tongues foldable thereon and having said crease extending thereinto, side flaps formed with the back portion and having attaching portions at their free ends secured vertically to the inner face of the front portion at its outer edges, said side flaps having central vertical folding creases lying coincident with the creases in the end tongues when the latter are secured to the outer faces of the end flaps to permit the envelop to collapse with the front and back portions in contact, said side flaps also having inclined folding creases between their upper corners and their central creases to fold downwardly and outwardly, a cover flap carried by one of said portions and having a central folding crease permitting it to extend into said downwardly folded portions of the side flaps and between the front and back portions and a sealing flap for the envelop.

In testimony whereof, I affix my signature, in presence of two witnesses.

MARIE D. AABERG.
